UNITED STATES PATENT OFFICE.

EHRHART SCHOTT AND WILHELM HAUG, OF LEIMEN, NEAR HEIDELBERG, GERMANY,
ASSIGNORS TO THE FIRM PORTLAND-CEMENTWERKE HEIDELBERG-MANNHEIM-
STUTTGART, AKTIENGESELLSCHAFT, OF HEIDELBERG, GERMANY.

BURNER FOR PULVEROUS FUEL.

Application filed July 16, 1923. Serial No. 651,935.

To all whom it may concern:

Be it known that we, EHRHART SCHOTT and WILHELM HAUG, both citizens of the German Republic, and both residing at Leimen, near Heidelberg, Germany, have invented 5 certain new and useful Improvements in Burners for Pulverous Fuel, of which the following is a specification.

This invention relates to an improved 10 burner designed for pulverous fuel, especially for coal dust. The invention has principally for its object to inject the fuel in combination with air for combustion into the fire box of the coal dust furnace in such 15 a manner that the coal dust which is per se difficult to ignite ignites instantaneously and that it is entirely burnt in the ignition space of the furnace within a very short time so that the slags may settle in the 20 ignition space and are not carried along into the flues and heating chambers.

This invention has further for its object 25 to protect the burner proper against the action of the extraordinarily high temperature in the ignition chamber of the furnace and to make the surface of the burner which is exposed to the action of this heat as small as possible. The invention has again 30 for its object to render the combustion economical so that the furnace possesses a high efficiency.

The invention will be best understood 35 from a consideration of the following detailed description taken in connection with the accompanying drawings forming a part of this specification, with the understanding that while on the drawings one embodiment of the invention is disclosed, the invention is not confined to any strict 40 conformity with the showing of the drawings, but may be embodied in any manner which does not make a material departure from the salient features of the invention.

In the drawings:

Fig. 1 shows partly in plan view and partly in horizontal section a burner constructed according to the invention.

Fig. 2 shows the burner partly in side elevation and partly in vertical section,

Fig. 3 is an end view of the burner seen in the direction of the arrow α (Fig. 1).

A mixture of coal dust and air for combustion is supplied to the burner by the pipe a , the special apparatus for the pro-

duction of pulverous fuel and for the ad- 55 mission of the same to the pipe a being not shown as they are common and well known and need no further description. The mouthpiece of the burner which is co-axial with pipe a is connected with this pipe 60 by connecting tube b' of the same diameter as the pipe a and consists of a fan shaped part b terminating in a narrow slot-shaped exit c . In the fan shaped part b and in the connection tube b' several main parti- 65 tions d are arranged. Between these main partitions d auxiliary partitions e are ar- ranged in the fan shaped part b . The mouth c of the burner is bricked into the brick work f of the ignition and combustion 70 chamber (not shown in the drawing) so that this mouth c of the burner is flush with the inner surface f' of the brickwork, no part of the burner projecting into said cham- 75 ber.

The mixture of fuel and air entering the connecting tube b' is subdivided into sev- 80 eral jets. As the thin sharp edges of the main partitions d offer no resistance to the pulverous fuel the main jets are transferred without shocks into the main channels. By the auxiliary partitions e in the main chan- 85 nels the main jets or currents are subdivided again without shock. In this manner the jet flowing in from the pipe a is gradually subdivided into numerous independent cur- 90 rents of favorable shape which, after hav- ing flowed through the mouth c of the burner into the ignition or combustion cham- ber, are instantaneously ignited and burnt completely. The whole process of the sub- 95 division and transformation of the jet of fuel and air mixture is carried out without any appreciable loss of energy and without the possibility that the pulverous fuel is precipitated in the burner by the action of shocks.

The burner itself is, with the exception of the very small mouth c , perfectly pro- 100 tected by the brickwork so that it can serve for a very long time.

The direction of the supply pipe a may be selected at will. The auxiliary parti- 105 tions e may also extend into the tubular connection b' or all the partitions might terminate in the fan shaped part b .

We are aware that it has already been proposed to construct fuel dust burners hav-

ing a fan like expansion and provided with partition for dividing the burner into a plurality of channels; therefor we do not claim broadly such matter but what we claim is:

5 We claim:—

In combination with a furnace having walls of brick work, a burner for pulverous fuel consisting of a supply pipe of circular cross-section for the feeding of the mixture

10 of fuel dust and air, and of a mouth piece in coaxial connection with said supply pipe, said mouth piece expanding from the circular cross-section of the supply pipe into a narrow slot-shaped exit at its free end and

15 having a plurality of main and auxiliary partitions, the main partitions extending

from the free end of the mouth piece over its whole length into the adjacent end of the supply pipe, the auxiliary partitions being shorter than the main partitions, the partitions subdividing the mixture of fuel dust and air so that it enters the furnace in a plurality of independent currents, the front end of said mouth piece being flush with the brick work of the furnace. 20 25

In testimony whereof we affix our signatures in presence of two witnesses.
